No. 13,423

Nov 14, 1882

UNITED STATES PATENT OFFICE.

JOHN L. POPE, OF CLEVELAND, OHIO.

DESIGN FOR A CARRIAGE-STEP.

SPECIFICATION forming part of Design No. 13,423, dated November 14, 1882.

Application filed August 2, 1882. Term of patent 14 years.

To all whom it may concern:

Be it known that I, JOHN L. POPE, of Cleveland, in the county of Cuyahoga and State of Ohio, have invented and produced a new and original Design for Carriage-Steps, of which the following is a specification, reference being had to the accompanying photographic illustration, forming part thereof.

My invention relates to a new design for carriage-steps; and it consists in providing the tops thereof with raised bars or ribs so disposed as to form in outline a series of polygonally-shaped figures, as will be hereinafter more particularly specified and claimed.

In the accompanying photograph the metallic carriage-step is shown as ornamented on its upper face with raised portions or work cast thereon and forming at each corner of the square step an elongated hexangle, which I have marked A. Within each hexangle the raised work is made to form a square, which will be found marked with the letter B. Running around nearly the whole extent of the step will be seen the figure of a large octangle, portions of four of the sides of which appear to pass underneath the center of each of the four hexangular figures A. This octangle I have designated by the letter C. Inside of the octangular figure are shown four hexangles, D D and E E, the latter two of which being somewhat smaller in size than the former two. Intermediate of and contiguous to the two six-sided figures D D is formed by the raised work a diamond-shaped figure, F, when viewed from either of the sides or edges of the step, or a square figure when viewed

obliquely or from either of the corners of the step. From each of the four figures A extends obliquely inwardly toward the center of the plate a short piece of the ribbed work, a, until it reaches the diamond-shaped figure F, and from each of the squares B similar bars, a', run along toward the middle of the plate until they reach the hexagonal figures D D; and bars a² run also from the said squares B until they join the hexangles E E.

Although I have shown the parts of the plate included within the hexangles D E and squares B F as open, yet I do not consider that an essential feature of my design, as the general effect of the ornamentation would be the same were I to leave no openings or spaces.

The distinctive feature of my design rests in the employment of raised work forming hexagonal figures at each corner of the step, square figures within the latter, the figure of a large octangle outlining nearly the whole superficial area of the plate, and within which forming five smaller polygonal figures.

What I claim as my new design, and desire to secure by Letters Patent, is—

A carriage-step, provided with ribbed or raised ornamentation, forming hexangular figures A, octangle C, squares B, and polygonally-shaped figures D E F within the octangle, substantially as shown.

In witness whereof I have hereunto set my hand this 31st day of May, 1882.

JOHN L. POPE.

In presence of—

A. A. POPE,
C. M. COPP.
